PARACHUTE AND MEANS FOR PROJECTING
AND OPERATING THE SAME

Alfred L. Ruthven, Denver, Colo.

Application February 1, 1943, Serial No. 474,240

9 Claims. (Cl. 46—86)

1

This invention relates to parachutes attached to a projectile, in collapsed condition during the projected flight of the projectile and opened to suspend the projectile or other object during its fall, and to means, combined with such projectile for projecting the same.

Objects of the invention are the provision of (a) improved means associated with the projectile for directing or guiding the projectile, (b) improved means for detachably attaching the parachute to the projectile, (c) combining said guiding means and said attaching means to insure detachment of the crown from the projectile at the predetermined point in the flight of the projectile, (d) a device combined with said projectile for projecting the same, (e) an improved projectile.

Having in view the foregoing and other objects, all of which shall more fully hereinafter appear, the invention comprises certain novel constructions, combinations and arrangements of parts hereinafter defined in the claims, the preferred embodiments of which shall be now described, the same being illustrated in the accompanying drawing in which

Fig. 1 is a side elevation of a projectile with parachute attached ready to be projected.

Fig. 2 is a view illustrating said projectile in the course of reversing from its projected flight to its return flight just after the guiding means have turned the projectile to position for detaching the crown of the parachute, the parts being illustrated as they are just after the detachment of the crown.

Fig. 3 is an elevation of said projectile in its downward course supported by the opened parachute.

Fig. 4 is a side elevation of said projectile, carrying the parachute, and positioned in and combined with a projection device.

Fig. 5 is a fragmentary view on an enlarged scale of a portion of the combined projectile and projecting means, being mostly in longitudinal, vertical section.

Fig. 6 is a section on line 6—6 of Fig. 4.

Fig. 7 is a fragmentary view showing a modification of the crown attaching hook on said projectile.

Fig. 8 is a view similar to Fig. 1 but illustrating improved means for taking up slack in the attaching cord.

Fig. 9 is a view of a distended parachute in reverse, that is, looking upward into the parachute when spread out to its limit and illustrating a preferred embodiment of the parachute.

Fig. 10 is a fragmentary detail view illustrating the construction at the apex of the parachute illustrated at Fig. 9, but on an enlarged scale.

Fig. 11 is a view of a fragment of the projectile and parachute and illustrating an improved means of balancing the projectile in flight.

2

Fig. 12 is a side view of Fig. 11.

Fig. 13 is a view of a fragment of a modified form of projectile and parachute attaching means, being another embodiment of the invention.

Fig. 14 is a view similar to Fig. 1 but illustrating a modification of the parachute-top-attaching and releasing means and modified structure for balancing the projectile in flight.

Fig. 15 is a side view of the top portion of Fig. 14.

Fig. 16 is a fragmentary detail of the form of attaching and releasing means illustrated at Figs. 14 and 15.

Fig. 17 is a section on line 17—17 of Fig. 16.

Fig. 18 is a fragmentary view illustrating a further modification of the means for attaching and releasing the top of the parachute.

Fig. 19 is a section on line 19—19 of Fig. 18.

Fig. 20 is a view, similar to Fig. 1 but of a projectile adapted to be projected by hand, without projecting means, such as a bow or gun, and illustrating means for allowing the parachute to wholly detach itself from the projectile.

The projecting means shall, hereinafter for brevity, be referred to as a "gun."

The invention is described as follows, the references being to the accompanying drawing illustrating the preferred and modified embodiments.

The projectile 1 is a shaft, which may be similar to the shaft of an arrow, provided with a notch 2 in its base and a tip including a weight 3 and, preferably a point 4 of padded or rubber-like material.

The projectile is provided with means, as stud 5, positioned near the butt or rear end of the projectile, for attaching, as at 6, the shroud lines 7 of parachute 8 which is provided with a loop 9 attached to the crown of the parachute by suitable means as cord 10.

The projectile carries, near its tip, means, as hook 11, adapted to detachably engage loop 9. The cooperation of loop 9 and hook 11 is such that the loop will engage the hook while the projectile is in projected flight. This is simply accomplished by inclining the hook forwardly, as illustrated, so that the resistance of the parachute to the air during such flight will draw the loop 50 down next the projectile and hold the loop securely on the hook as long as such flight continues.

As the projecting force is spent the heavy tip of the projectile causes the projectile to reverse and fall tip down and the detachment of loop 9 from hook 11 during the early stages of such reversal of the projectile is necessary to assure the most successful operation.

For this purpose I provide means which will, by reason of air resistance, keep the projectile, while it is reversing, always in position with hook 11 on the upper side of the projectile.

When the projectile begins to reverse, the air resistance on the parachute changes direction relative to the projectile. During projected flight such air resistance acts in a direction longitudinally of the projectile. As the projectile reverses the resistance acts on the parachute at an increasing angularity to the projectile and when the projectile has reversed sufficiently the pull of the air on the parachute is at such an angle to the projectile that loop 9 is pulled off hook 11, all as illustrated at Fig. 2, whereupon the projectile assumes the point-down position, illustrated at Fig. 3 and the downward pull on the shroud lines causes the parachute to open whereafter the device floats down in the position illustrated at Fig. 3.

The means provided for keeping the projectile hook-side up during reversal, may be of the utmost simplicity and I preferably provide, for this purpose, plain vanes or fins 12, of sheet fiber or the like, which may have one of their edges set into the projectile and pinned therein as at 13. These fins or vanes project from the projectile in line with hook 11 and it is obvious that the air resistance of these vanes or fins will cause the vanes or fins to be always on the upper side of the projectile when it is moving in a line not parallel to its own longitudinal axis, as in reversing at the end of a projected flight. As hook 11 is on the same side of the projectile as the vanes or fins, the hook will always, during anything but a longitudinal movement of the projectile, be on the upper side of the projectile.

It is understood that even without the fins or vanes 12, the air resistance on the parachute, during any but longitudinal movement of the projectile, would tend to keep the projectile hook-side up as the pull of the parachute would be on hook 11 and stud 5 which are in alignment on one side of the projectile.

The provision of the fins or vanes, however, tends to assure the maintenance of the proper position of the projectile and the consequent release of loop 9 from hook 11 at the desired time.

It will be understood that the functions of stud 5 and the adjacent vane 12 may be combined by providing means, as hole 14, in the vane for attachment of the shroud lines directly to the vane. The positioning of stud 5 substantially back of the longitudinal center of the projectile and of hook 11 substantially forward of such center are, obviously, essential to the efficient operation of the device in manner illustrated and described.

The projectile may be shot from a bow, the notch 2 being provided for engaging the bow string for that purpose.

Preferably a gun is provided for projecting the device and the device and gun, combined for projection, are illustrated at Figs. 4, 5 and 6 in shape preferable for use as a toy, wherein the gun is illustrated as having a stock 15, a barrel 16 with a handhold 17, the barrel being longitudinally slotted in its top as at 18 to receive stud 5 and vanes 12.

The barrel 16 is also provided with slots 19 in its sides in which slot pin 20 may move longitudinally of the barrel. Pin 20 is adapted to fit in notch 2 and means, such as rubber bands or springs 21, secured to the forward part of the barrel as at 22, engage pin 20 and are stretched when projectile 1, with pin 20 seated in notch 2, is inserted into the barrel to the position shown at Figs. 4 and 5.

The gun is provided with a suitable releasable detent as trigger 23 having hook 24 adapted to

engage notch 25 in the projectile for holding the projectile in position with bands or springs 21 stretched substantially to their limit. The release of and firing the projectile with the attached parachute will obviously result from the retraction of the trigger 23.

Spring 26 and guard 27, of ordinary construction and for common and obvious uses, may be provided.

I preferably provide easily releasable means for holding the slack shroud lines to insure against snarling. This may consist of a spring 28 affixed to the stock and adapted to exert just sufficient pressure to retain slack shroud lines until subjected to the pull resulting from releasing the projectile, whereupon the lines will easily detach from spring 28.

The means for engaging loop 9 to the projectile may, obviously, be formed in different ways as, for example, forming a notch 29 in the arrow, as illustrated at Fig. 7. This construction has the advantage of bringing loop 9 substantially to the center of the projectile so that the pull of the parachute on loop 9 will be exerted on the projectile substantially at its center.

In Fig. 8 I have illustrated means for taking up the slack of the shroud lines in case of projection from a bow. These means consist of a cord 30 attached to the projectile back of the point of attachment of the shroud lines to the projectile, as at 31, and passed through the slack of the shroud lines and pulled back, to take up such slack, and passed through notch 2 where it will be held by the bow string until released. In this figure I have, for simplicity of illustration, shown a cord 1a attached to the shroud lines and thence to the vane 12 at 14, and have shown cord 30 taking up the slack in cord 1a which will, in turn, also take up the slack in shroud lines 7.

I have, at this figure, also illustrated the point 33 of the projectile larger than the shaft in order to eliminate the use of metal. The necessary weight may be provided by enlarging the point even though it be made of the same material as the shaft.

At Figs. 9 and 10 I have illustrated a parachute constructed especially for use as a part of this invention and in combination with the projectile. Such parachute has an outer layer or member 34, shroud lines 7 and a lining 35. A snap socket 36 is mounted in the center of the parachute and to it the cord 10 may be attached. A snap button 37, adapted to snap into socket 36, is provided with eyelets to which the upper ends of the shroud lines are attached as at 38. The lining 35 is provided with an orifice 39 through which the knob 37a of the button may be projected for insertion in the socket. This orifice is preferably surrounded by suitable reinforcement 40. The shroud lines 7 are attached to the edges of the outer layer 34 as at 41. The lining is preferably slightly smaller than the outer layer so that the edge of the lining falls short of the edge of the outer layer as clearly illustrated at Fig. 9 and thus the lining is wholly inside the outer layer.

When the socket 36 and button 37 are separated the lining may be positioned as a lining for the outer layer and above the lines 7. Knob 37a is then inserted through orifice 39 and into socket 36 thus securing the lining in desired position between the outer layer and the shroud lines, in which position it will open with and act as a lining for the outer layer.

By this construction it is possible to use for

the outer layer a fabric or other material which, while having sufficient strength, may be cheap and quite porous with a lining which is not porous but cheap and having little strength, such as paper, thus providing a parachute which is strong and nonporous but made of very cheap materials, having a cheap and easily replaceable lining.

It may be found that attaching the parachute at one side of the projectile results in deflecting the projectile from a straight course by reason of the air resistance of the parachute.

To balance the air resistance of the parachute I attach an inclined leaf 41 to the side of the projectile opposite that to which the parachute is attached. This is clearly illustrated at Figs. 11 and 12. The effect of the leaf there illustrated, in balancing the air resistance of the parachute, will be obvious.

At Fig. 13 I have illustrated another embodiment of the invention in which the central portion of the shaft 1 of the projectile is formed of two spaced parts 43 and 43a between which the parachute hangs by the cord 10 and loop 9 from a hook 44 positioned at the center of the projectile whereby, during projected flight of the projectile, the parachute will hang along the longitudinal center of the projectile thus substantially equalizing the air resistance on all sides of the device during the projected flight.

Fig. 14 illustrates a projectile and parachute combination like that illustrated at Fig. 8 except that at Fig. 14 a different structure for releasably attaching the tip of the parachute to the projectile and a modified air-pressure-balancing leaf are illustrated, the details thereof being illustrated at Figs. 15, 16 and 17.

This embodiment of the releasable attaching means comprises a tab 45 attached to cord 10 as at 46, which may be adapted to engage the vane 12 by means of notch 47 and is provided with an orifice 48 for engagement with pin 49 which is mounted in, and projects from the shaft of projectile 1, whereby the tip of the parachute may be attached to the projectile by hanging tab 45 onto pin 49.

To hold tab 45 in engagement with pin 49 during projected flight of the projectile I provide a flap 50, adapted, as by loosely hanging the upper end of the flap onto pins 51, to swing toward or away from the projectile, as clearly illustrated at Fig. 14. When the projectile is in projected flight the air pressure holds flap 50 against tab 45 and thus maintains the engagement of tab 45 with pin 49. When the projectile turns in the manner illustrated at Fig. 2, flap 50, being on the same side of the projectile as vane 12, will be on the upper side of the projectile, which is then beginning to fall, so that the air pressure on flap 50 will cause it to swing out to dotted line position at Fig. 14 leaving tab 45 free to move away from the projectile. At the same time and for like reason, the parachute will leave the projectile in the manner illustrated at Fig. 2 resulting in tab 45 disengaging from pin 49 in the same manner that ring 9 disengages from hook 11 as shown at Fig. 2.

At Figs. 18 and 19 I illustrate another form of releasable attaching means for the tip of the parachute comprising a link 52 carried by cord 10 and carrying a lug 53, the lug in turn carrying a pin 54 adapted for insertion into and removable from irregular slot 55 in vane 12 when link 52 is in position indicated in broken lines at Fig. 18 but to lock to vane 12 when link 52 is other-

wise positioned, suitable means, as leaf spring 56, being provided for snapping the member 52-53-54 out of engagement with vane 12 when link 52 is turned to broken line position.

To attach the parachute tip to the projectile link 52 is positioned as indicated in broken lines and lug 53, with its pin 54, is inserted through slot 55, against the pressure of spring 56, and then turned to solid line position in which position it is locked to vane 12 and in which position it will remain during the projected flight. When the projectile turns to the position illustrated at Fig. 2 the air pressure forces the parachute away from the projectile and lifts link 52 to the broken line position whereupon spring 56 snaps member 52-53-54 out of slot 55 and releases the tip of the parachute from the projectile.

The balancing leaf 57 shown at Figs. 14, 15 and 16 may be used with any form of projectile thus

far described in place of the leaf 41 shown at Figs. 11 and 12 though the use of any such balancing means will usually be unnecessary with the form of projectile disclosed at Fig. 13 which is substantially balanced. Balancing leaf 57 is simply a leaf or sheet of thin stiff material attached to point 33 at a suitable angle to the axis of the projectile and it is most conveniently attached by beveling the point to the desired angularity and attaching the leaf to the bevelled face by any suitable fastening means, not shown. The tip of the point 33 should project beyond the end of leaf 57 as shown at Figs. 14 and 15 so that the tip, rather than the leaf, will take the force of the impact when the projectile drops to the ground. It is, therefore, preferable to inset the leaf in the bevelled face of the point 33 as clearly shown in the drawing.

At Fig. 20 I have illustrated a form of projectile and parachute adapted to be projected by hand without the use of gun, bow or other mechanical projector. This embodiment comprises a shaft 1 having vanes 12 and parachute 8 and suitable releasable parachute - tip - attaching means, those means illustrated at Figs. 1, 2 and 3 being shown in this figure.

In order to adapt this embodiment of my invention for projection by hand I provide a light weight hand hold as ball 58 attached to the projectile by suitable means as cord or wire 59 while to the point of the projectile I attach, in similar manner, an object heavier than ball 58 as ball 60. Holding ball 58 in the hand, the operator can swing the device in a circle, preferably in a vertical plane, and, when desired, let go of ball 58 whereupon ball 60, by centrifugal force, will carry the device into the air and, when the projecting force is spent, the projectile will follow the course indicated at Fig. 2 and the tip of the parachute will be released in the same manner as shown at Fig. 2.

In order to hold the parachute crown against release during the whirling of the device and still provide for its automatic release when the projectile turns over at the end of the projected flight I pass the cord 59 through a bore 63 in the base of the projectile and out through a hole 64 and thence along the projectile to a hole 65 passing through the projectile just to the rear of hook 11 and on the end of cord 59 I provide a loop 66 adapted to engage hook 11 overlying ring 9 whereby when the device is whirled cord 59 will be drawn taut and hold loop 66 tightly on hook 11 thus holding ring 9 on hook 11. When the device is released the tension on cord 59 is released and when the device turns to the position

as illustrated at Fig. 2, there will be substantially no tension on cord 59 and the pull of parachute 8 will release both ring 9 and loop 66 from hook 11.

In this embodiment the shroud lines may be fastened to the projectile or to a lug or to the vane 12 near the base of the projectile in any manner as heretofore shown and described or in any other suitable manner. At Fig. 20, however, I have illustrated a releasable attachment of the shroud lines as well as of the tip of the parachute whereby the parachute will be wholly released from the projectile. This comprises an elongated hook 61, conveniently formed by cutting away a portion of vane 12, adapted to receive a ring 62 carried by the shroud lines. The hook is pointed toward the base of the projectile so that when the projectile turns over following the spending of the projecting force, the tip of the parachute will be first released, as heretofore described, and, as the parachute opens and slows the fall it will retard the fall of the base of the projectile, until the projectile has reversed its position sufficiently to permit hook 61 to slide out of ring 62 whereupon the projectile will drop and the parachute will float down carrying ring 62, it being understood that this ring is made of sufficient weight to act as a balance weight in floating the parachute to earth.

I have here illustrated and described this invention as a toy. By obvious modifications in size, strength and mechanical detail it may be put to practical uses on a much larger scale.

While I have shown and described many details of construction I am not to be limited to such details but desire protection as well upon the many mechanical equivalents which will readily occur to those skilled in the art.

I claim:

1. In a device of the character described, a projectile having a relatively heavy tip portion, and a parachute having shroud lines, means for attaching the shroud lines of the parachute to the rear portion of the projectile and a releasable engagement of the parachute crown with the projectile's tip portion, said engagement comprising members carried respectively by, and on one side of, the projectile and by the crown adapted to interengage and be held in interengagement by a pull exerted on the parachute parallel to the projectile axis but to disengage by a pull exerted on the parachute at an angle to the axis of the projectile and a fin affixed to the projectile and aligned with said engaging member on one side thereof whereby to maintain the releasable engagement means on the upper side of the projectile during its arc of travel resulting from the expenditure of the projecting force.

2. In a device as defined in claim 1, means attached to the projectile and adapted for engagement with the shroud lines of the parachute and with a projecting apparatus whereby to tension the shroud lines, the engagement with the projecting apparatus being releasable by and coincident with the projection of the device.

3. In a device as defined in claim 1, the parachute being engaged at one side of the projectile, whereby, during projected flight of the projectile, the air resistance of the parachute tends to deflect the projectile from a straight course, and a vane carried by the projectile at an inclination relative to the axis of the projectile and thereby adapted to balancingly off-set said deflecting tendency of the parachute.

4. In a device as defined in claim 1, the middle portion of the shaft of the projectile being divided, and the means carried by the projectile for engaging the crown of the parachute being disposed at the axis of the projectile between the separated parts of the shaft whereby the parachute is suspended substantially along the axis of the projectile.

5. In a device as defined in claim 1, the releasable parachute-crown-engaging means comprising a pin carried by the projectile, a tab connected to the parachute crown and adapted, by an orifice therein, to engage the pin when the tab lies substantially parallel with the projectile but to disengage from the pin when moved to a substantial angularity with the projectile and a flap hingedly carried by the projectile forwardly of the pin and adapted to overlie the tab and maintain said engagement whenever, as during projected flight of the projectile, air resistance is substantially equal on both sides of the flap.

6. A parachute comprising an outer layer of relatively strong material and a lining of non-porous material, a plurality of cords attached at spaced points to the edge of the outer layer and converging at the center, a fastening member comprising two releasably interengaging parts, one part being mounted in the center of the outer layer and the other part being attached to said cords at said point of convergence, said lining lying between the outer layer and the cords and having a central orifice adapted to permit the interengagement of said parts therethrough.

7. In combination with a device as defined in claim 1, a projection apparatus, means engaged with the shroud lines of the parachute and adapted for engagement with the projectile and with the projecting apparatus whereby to tension the shroud lines, the engagement with the projecting apparatus being releasable by and coincident with the projection of the projectile.

8. In a device as defined in claim 1, the projectile having a handle flexibly attached to its base and being weighted at its point, whereby the toy may be manually swung in a circle and projected by centrifugal force, there being means during said swinging for holding the parachute crown attached to the projectile.

9. In a device as defined in claim 1, the shroud-line-engaging means being adapted to disengage from the projectile by a pull toward the rear of the projectile after the crown has been disengaged.

ALFRED L. RUTHVEN.
